chinery Corporation, Flemington, N. J., a corpo-
ration of New Jersey

Application October 27, 1941, Serial No. 416,674

12 Claims. (Cl. 12—50)

This invention relates to heel building machines, and is herein illustrated and described as embodied in a machine including forms in which pasted heel lifts are assembled by hand or otherwise, after which the assembly of lifts is placed under pressure which is maintained until the paste has set sufficiently to prevent the lifts from becoming separated from each other.

It is an object of the invention to provide an improved machine of this type, the use of which will insure the accurate production of heels of uniformly high quality rapidly, economically, and efficiently, with a minimum amount of effort and skill on the part of the operator.

With this in view, the illustrated machine embodies a plurality of heel assembling forms mounted upon a rotary table or other movable carrier in such a manner that each form may be moved to and from a lift assembling station, and to and from a pressing station. At the pressing station pressure is applied, preferably automatically, by a fluid pressure operated ram capable of exerting very heavy pressure which, when the proper kind of quick setting paste is used, causes the component lifts of the heel to become thoroughly and firmly stuck together in a very short period of time. The various mechanisms of the machine are preferably power-operated, their operation being controlled by a treadle, a single depression of which permits the machine to go through one complete cycle of operation.

A feature contributing to accurate operation of the machine consists in the employment of interlocking means for so controlling the operation of the pressure ram and the movements of the heel forms that the ram cannot operate while the forms are moving, nor when no form is in exact register with the ram.

Other novel and useful features are to be found in the arrangement of the means for supplying and controlling the supply of fluid under pressure to the heel pressing ram.

These and other features of improvement will be better understood and appreciated from the following detailed description of an illustrative machine, to be read in connection with the accompanying drawings, in which

Fig. 1 is a perspective view from a viewpoint at the left of the lift assembling station;

Fig. 2 is a similar perspective view from a viewpoint at the right of the lift assembling station;

Fig. 3 is a view, partly in vertical section, show-

ing the mounting of the rotary table which carries the heel forms;

Fig. 4 is a plan view, partly in horizontal section, of the table controlling mechanism at the pressure applying station;

Fig. 5 is a detail view in front elevation, showing the heel loosening means for one of the heel forms;

Fig. 6 is a view, partly in elevation and partly in section, of the apparatus for controlling the application of hydraulic pressure and the positioning of the table;

Fig. 7 is a plan view of a portion of the apparatus shown in Fig. 6;

Fig. 8 is a view in elevation of a portion of the apparatus shown in Fig. 6 with certain of the parts in different positions;

Fig. 9 is a view, partly in elevation and partly in section, upon the line IX—IX of Fig. 8;

Fig. 10 is a view similar to Fig. 9, but showing the parts in different positions;

Fig. 11 is a view similar to Fig. 10 showing the operation of the table locking mechanism; and

Fig. 12 is a view on an enlarged scale of a detail of the safety control for the hydraulic ram by which pressure is applied to an assembled heel.

Referring now to the drawings, 20 indicates a base or column upon which the various operating mechanisms of the machine are mounted, the 30 said base extending upward to provide an overhanging bracket 22 for the support of a hydraulic ram 24, which will be described in detail hereinafter. A motor 26 mounted upon the column 20 supplies power for rotating a movable carrier, 35 shown herein as a heel form supporting table 28, and for operating a pump 30 which creates fluid pressure in the hydraulic system. The pump has upon its shaft a pulley 32 which is driven by a belt 34 from a pulley 36 upon the motor shaft, and another pulley 38 also upon the motor shaft is connected by a belt 40 to a pulley 42 which drives conventional speed reducing gearing contained in a housing 44. From this gearing arises a vertical shaft 46 carrying a small pulley 48 which is connected by a belt 50 to a large pulley 52.

As best shown in Fig. 3, the pulley 52 has a threaded hub 54, screwed into a split bearing ring 56 which may be clamped to the hub by tightening a screw 58. The ring 56 rests upon a ball bearing 60 supported upon the machine base 20 and surrounding a stationary post 62 which extends upward from the said base.

The table 28 has a downwardly extending hub 64 secured by a set screw 66 to a sleeve 68 rotat-

able about the post 62 upon which it is journaled to rotate. The sleeve 68 is integral with a cam 70, the base portion 72 of which rests upon a friction disk 74 interposed between the said base portion and the upper face of the pulley 52.

In the operation of the elements just described, the pulley 52 is rotated continuously by the motor 26 and the table 28, the weight of which is supported by the friction disk 74, will be rotated likewise about the upright post 62 unless it is forcibly held from turning, in which event the frictional driving connection between the pulley 52 and the table will slip, permitting the table to remain stationary while the pulley continues to rotate.

For the purpose of controlling the movements of the table 28 there is, on the underside of the table, an abutment 76 (see Figs. 1 to 4) to the end of which is affixed a shock-absorbing pad 78 of leather or other suitable material. A stop latch 80 is arranged to be interposed in or removed from the path of movement of the abutment 76 which moves, with the rim of the table, in a circular path in a counter-clockwise direction, as viewed from above.

The latch 80 is pivoted at 82 between ears 84 projecting horizontally from the upper end of a slide 86 which is guided for vertical movement upon the face of a stationary plate 88 secured to a shelf 117 upon the machine base 20. The slide 86 is maintained in sliding engagement with the plate 88 by gibbs 90 (see Figs. 6 and 8) and a stud 92 screwed into the plate 88 serves to limit the movement of the slide 86 in a downward direction. A spring-pressed plunger 94 in the latch 80 tends to swing the latch into the vertical position illustrated in Figs. 9 and 10 but when the upper end of the latch is struck by the pad 78 on the abutment 76 the latch can swing about its pivot 82 until a stop screw 96, threaded adjustably through the lower end of the latch, strikes the slide 86 whereupon the parts will be in the positions illustrated in Fig. 11 and the rotation of the table 28 will be positively stopped.

In order to prevent the table from rebounding when it is stopped by engagement of the pad 78 with the latch 80, a block 98 having the conformation shown in Fig. 4 is bolted securely to the outer face of the abutment 76 which is rigid with the table and a detent plunger 100 having an antifriction roll 102 in its outer end is arranged in a tube 104 containing a spring 106 for projecting the plunger to a position behind the end of the block 98. The forward portion of the block is so shaped that the roll 102 will ride over it easily until the block has passed the detent, which then moves in behind the block and prevents rebound of the table. For adjusting the tension of the spring 106 a screw 108 is provided and the adjustment may be such that the resistance of the detent to the movement of the block 98 past it will exert enough braking effect upon the table to almost stop its rotation, with the result that the impact of the abutment 76 against the stop latch 80 will not be very great. This structure is advantageous in that it provides for stopping the table very exactly, with a minimum of shock, at a point which can be determined accurately by adjustment of the stop screw 96 in the latch. The detent roll 102, pressing with considerable force against the inclined rear end of the block 98, holds the table abutment 76 firmly against the stop latch.

Mounted upon the table 28 is a suitable number (herein shown as two) of heel-assembling

forms 110 which are identical with each other and may be substantially like that disclosed in United States Letters Patent No. 2,238,938, granted April 22, 1941, upon an application by Fred Ashworth, to which patent reference may be had for a complete disclosure of the details of their construction. There is one abutment 76 on the under side of the table for each such form and in the bottom of each form is a vertically movable ejector pin 112 (see Fig. 5) which at a suitable point in the rotation of the table engages and rides up on a stationary cam 114 for the purpose of loosening a heel in the form sufficiently to permit it to be removed easily by the operator. The cam 114 is so positioned that the pin 112 drops off it before the heel form reaches lift-assembling position.

In order to support the table 28 unyieldingly against the heavy downward pressure exerted by the hydraulic ram, a block 115 is provided on the under side of the table beneath each heel form, and the solid, stationary shelf 117 upon the machine column 20 is arranged directly beneath the ram. When a heel form is beneath the ram the corresponding block 115 rests squarely upon the shelf 117 which serves to sustain the pressure.

In order to release the table 28 from restraint by the latch 80 and to permit it to move a half-revolution, during which a heel form will be carried from assembling position to pressing position, operator controlled means is provided for lowering the slide 86 from the upper position shown in Figs. 6, 10 and 11 to the lower position shown in Figs. 8 and 9. When the slide is thus lowered the latch 80 is moved below the level of the abutment 76 and the table is free to be rotated by the motor 26, through the friction drive 74, until the next abutment arrives in position to engage and be stopped by the latch which, in the meantime, will have returned to its upper position in a manner presently to be described. For the purpose of lowering the slide 86 and the latch 80 carried thereby a stud 116, screwed into the slide and extending through a slot 118 in the plate 88, is engaged in a slot 120 in a lever 122 which is movable about a stationary pivot 124 and is normally drawn downward by a spring 126 anchored to any convenient stationary part of the machine. When the table is held stationary by the latch 80 the latch and the slide 86 are held in their upper position, against the tension of the spring 126, by a slidable pin 128 guided for horizontal reciprocating movement in a stationary supporting sleeve 130 affixed to one of the gibbs 90 (see Figs. 6 and 7). The pin 128 passes through an aperture 132 in the lower arm of the latch 80 when the pin is in latch-supporting position but the pin is connected by a link 134 to an upright arm 136 rigid with a treadle bar 138 by depression of which the pin may be withdrawn from the aperture in the latch, permitting the latch and the slide 86 to descend and release the table. As soon as the latch has moved downward even a very small amount releasing the treadle will not affect the further operation of the mechanism since the aperture in the latch is no longer in alignment with the pin 128 and, therefore, the pin cannot re-enter the aperture, although a spring 140 beneath the treadle and a spring 142 acting upon the arm 136 both tend to move the arm and the pin 128 rearward.

In order that the latch 80 may again be elevated to stop rotation of the table at the proper time the

lever 122 is raised by the cam 70, which rotates with the table and engages a cam roll 144 mounted in the end of the lever. When the lever is raised by the cam 70 the slide 86 rises until the tip of the pin 128, which is beveled as shown at 146 (Figs. 6 and 7), engages the beveled walls 148 of an arcuate slot 150 in the latch 80, said slot being concentric with the pivot 82 and terminating in the aperture 132. The parts are shown in this position in Fig. 10 and it is not until the latch is struck by the next abutment 76 on the table and swung to the position shown in Fig. 11 that the pin 128 can re-enter the aperture 132, to permit the treadle bar 138 to rise and the arm 136 to move rearward.

The purpose of thus preventing the treadle from rising while the table is moving is to prevent the hydraulic ram 24 from descending during that time and this is accomplished by connecting the upright treadle arm 136 by a link 152 to the piston 154 of a hydraulic control valve 156 which controls the flow of fluid to and from the ram. Fluid under pressure is conducted to the valve 156 by a pipe 158 which enters the valve cylinder through an inlet port 160. From the valve cylinder the fluid passes out through an outlet port 162 and through a pipe 164 (Figs. 1 and 6) into the top of a stationary hollow piston 166 which is bolted to the overhanging bracket portion 22 of the machine collar. The stationary piston 166 is surrounded by a vertically movable cylinder 168 to the lower end of which is affixed the ram 24 which carries a heel-pressing die 170. The interior of the hollow piston and the interior of the cylinder are in communication with each other. The weight of the cylinder 168 is sustained, and the cylinder is normally drawn upward, by springs 172 but when fluid under pressure is admitted to the hollow piston the cylinder and pressure ram descend and apply pressure to the assembly of heel lifts beneath.

In order to dispose of any fluid which may leak past the piston 166 an annular chamber 169 which is formed in the upper end of the cylinder 168 is connected by a flexible hose 171 (Fig. 1) to a drain pipe 173 by which the fluid is returned to the fluid supply tank 180.

Referring again to Fig. 6, the piston 154 in the valve 156 has a reduced portion 174 which permits passage of fluid from the pipe 158 to the pipe 164 through the valve when the piston is in the left-hand position shown. When, however, the piston is moved toward the right, to the position indicated in dotted lines, the passage between the ports 160 and 162 is closed and the port 162 is connected to an exhaust port 176 from which a fluid discharge pipe 178 leads into the fluid supply tank 180. The springs 172 are thus permitted to lift the cylinder 168 and discharge the fluid contained therein back through the pipe 164, through the valve 156 and out through the pipe 178. It is apparent that as long as the sliding pin 128 is held forward by the latch 80 and the treadle is thus held depressed the valve piston 154 is kept in such a position that no fluid under pressure can be admitted to the piston 166 and cylinder 168. Remembering that this is the condition which exists while the table 28 is in motion, it will be clear that the ram 24 cannot be caused to descend until after the table has stopped.

The stop screw 96 is so adjusted that the table will be stopped by the latch 80 with one of the heel forms 110 accurately beneath the heel-pressing die 170 carried by the ram 24. At this time the cam 70 has passed out from under the cam

roll 144 and the impact of the abutment 76 against the latch 80 has caused the latch to swing to the position shown in Fig. 11, in which position the aperture 132 is in line with the slidable pin 128. Under the influence of the springs 140 and 142 the pin passes through the aperture and the treadle arm 136 swings rearward to the position shown in Fig. 6, moving the valve piston 154 to the position shown in solid lines. This shift of the valve piston connects the pipe 158 to the pipe 164 via the passage around the reduced portion 174 of the valve piston and admits fluid under pressure to the ram, causing the latter to descend and apply heavy pressure to a pile of pasted lifts previously assembled in the heel form which is now beneath the ram. This heavy pressure is maintained until the treadle 138 is again depressed.

The motor driven pump 30 draws fluid from the supply tank 180 through a pipe 182 (Fig. 2) and delivers it through the pipe 158 to the intake side of the valve 156. The pump, which runs continuously, delivers more fluid than is required and a conventional pressure release valve 184, connected to the pipe 158, which is set to open at the predetermined pressure which it is desired to maintain in the system, permits the excess fluid to escape through a pipe 186 back into the fluid supply tank 180. A pressure gage 188 connected by a pipe 190 to the supply pipe 158 indicates the amount of pressure in the system.

In order to dispose of the fluid supplied by the pump 30 when the piston 154 is in the forward position illustrated in dotted lines in Fig. 6, at which time no pressure on the ram is required, and to avoid the use of the extra amount of power that would be needed to maintain pressure in the supply pipe 158, an open waste port 192 is provided in the rear end of the valve cylinder 156 to permit the fluid supplied by the pump to escape freely back into the fluid supply tank 180 through an open pipe 194. The port 192 is, of course, closed by the head of the piston 154 when the piston is in its rearward position to permit fluid to flow to the ram.

In order to eliminate the possibility of the ram and the heel-pressing die 170 being forced down into an empty heel form, with the consequent possibility of damage to the machine, a safety device is provided for automatically stopping admission of fluid to the ram when the ram has descended to a predetermined point, regardless of whether or not it encounters any resistance. For this purpose a shut-off valve 196 (Fig. 1) is provided in the pipe 164. As shown, this is a gate valve of a conventional type which is opened and closed by a lever 198 upon which a spring 200 acts in a direction tending to close the valve. The valve is normally held open by an L-shaped trigger 202 arranged to hook over a pin 204 projecting upward from the lever 198. The trigger 202 is pivotally mounted at 206 in a stationary bracket 208 and a spring 210 acting upon the tail of the trigger tends to hold its hooked end down around the pin 204. Secured to a lug 212, projecting from the side of the pressure cylinder 168, by a clamp 214 is an upright rod 216 the upper end of which is bent at right angles to provide a tappet 218 which, when the cylinder has moved downward to a predetermined point, engages and trips the trigger 202, disengaging it from the pin 204 and permitting the valve 196 to close, which it does instantly. When this has occurred it is impossible for the cylinder 168 to move in either direction until the valve 196 has been reopened by hand.

Although the various mechanisms and their operation have been described in detail, a brief recapitulation of the operation of the machine as a whole will now be given. The operator, standing in front of the machine at the lift assembling station, assembles a pile of pasted heel lifts in the form before him and then depresses the treadle 138, thus retracting the pin 128 and the valve piston 154. Fluid pressure upon the ram 24 is thus released, allowing the ram to rise and the latch 80 to descend, whereupon the table 28 turns one-half of a revolution, to carry the heel around to the pressing station beneath the ram. During the time while the table was turning, the cam 70 has caused the latch 80 to be raised and, the tip of the pin 128 having entered the slot 150, the latch is supported in the path of the oncoming abutment 76 so that it will stop the table 20 when the heel form reaches the pressing station. Pressure of the abutment 76 against the latch alines the aperture 132 with the pin 128, permitting the treadle to rise and the valve piston 154 to move rearward to admit fluid under pressure to the ram, which descends to apply pressure to the freshly built heel.

The operator now proceeds to remove from the second heel form a previously pressed heel which has been loosened from the form by the ejector pin 112 when the latter passed over the cam 114 and then repeats his performance of assembling a pile of pasted lifts in the form while the previously built heel is held under pressure beneath the hydraulic ram. Experience has shown that when a suitable adhesive is used and a sufficient amount of pressure is applied the time required for assembling the lifts of one heel allows sufficient pressure dwell for the previously built heel.

Having described the invention, what is claimed as new and desired to be secured by Letters Patent of the United States is:

1. In a heel building machine, the combination of a movable carrier, a plurality of heel assembling forms mounted in spaced relation on said carrier, means for moving the carrier to position one of said forms at a time at a single pressure applying station and simultaneously to position another form at a lift assembling station, and means at the pressure applying station for applying and maintaining pressure upon a heel in the first form for any desired length of time while another heel is being assembled in the second form.

2. In a heel building machine, the combination of a rotary table, a pair of heel forms mounted in spaced relation on said table, means for rotating the table, means for locking the table against rotation, means operative only when the table is locked for applying and maintaining pressure upon a heel in one of said forms while another heel is being assembled in the other form, and a single means for releasing the pressure and unlocking the table.

3. In a heel building machine, the combination of a heel form movable to and from a pressure applying station, a support for said heel form, a reciprocable pressure ram at said station, means for moving the ram toward the heel form to apply pressure to a heel therein, and means controlled by the heel form support for preventing the ram from moving toward the form when the form is not in register with the ram.

4. In a heel building machine, the combination of a plurality of heel building forms sequentially movable to and from a pressure applying station, a reciprocable pressure ram at said station, means for moving the heel forms, mean for moving the

ram toward a heel form at the station to apply pressure to a heel therein, and means for preventing pressure applying movement of the ram except when a heel form is in register with the ram.

5. In a heel building machine, the combination of a rotary table, a plurality of heel building forms mounted on said table, a pressure ram, means for actuating the same, means for rotating the table, means for stopping the table with a heel form in register with the ram, and connections between the table stopping means and the ram actuating means adapted to prevent actuation of the ram unless the table is stopped.

6. In a heel building machine, the combination of a frictionally driven, rotary table, a plurality of heel forms mounted on the table, a pressure ram, means for actuating the same to apply pressure to a heel in one of the forms, a controller for the ram actuating means, a stop for holding the table with a heel form in register with the ram, and a single treadle operated means for actuating said controller and releasing said stop.

7. In a machine of the class described, the combination of a movable carrier, a plurality of heel forms upon said carrier, a pivotally mounted apertured stop latch movable into the path of a portion of the carrier, a fluid pressure operated pressure ram cooperating with the heel forms successively, a valve for controlling admission of fluid under pressure to the ram, valve operating means, and a pin on said valve operating means cooperating with the aperture in the stop latch to correlate the operation of the ram with the stoppage of the carrier.

8. In a heel building machine, a heel form movable to and from a pressure applying station, a fluid pressure operated pressure applying ram at said station, and means movable with the heel form for controlling the supply of fluid under pressure to the ram.

9. In a heel building machine, a heel form movable to and from a pressure applying station, a support for said heel form, a fluid pressure operated ram at said station, and means controlled by the heel form support for controlling the supply of fluid under pressure to the ram.

10. In a heel building machine, a heel form movable to and from a pressure applying station, a fluid pressure operated pressure ram at said station, means for supplying fluid under pressure to the ram when the heel form is at said station, and means for preventing the supply of fluid to the ram when the heel form is not in register therewith.

11. In a heel building machine, a movable heel carrier, fluid pressure operated means for applying pressure to a heel upon the carrier, means for controlling the supply of fluid to said fluid pressure operated means, and means on the carrier for controlling the operation of the fluid supply controlling means.

12. In a heel building machine, a heel form movable from a heel receiving station to a heel pressing station, a fluid pressure operated ram at said pressing station, means for controlling the supply of fluid to the ram, and means movable with the heel form for controlling the operation of the fluid supply controlling means to supply fluid to the ram when the heel form reaches said pressing station.
